UNITED STATES PATENT OFFICE.

CLAIR L. FARRAND, OF FOREST HILLS, NEW YORK.

DESIGN FOR A LOUD-SPEAKER CASING.

Application filed June 8, 1928. Serial No. 27,051. Term of patent 14 years.

To all whom it may concern:

Be it known that I, CLAIR L. FARRAND, residing at Forest Hills, N. Y., a citizen of the United States, have invented a new, original, and ornamental Design for Loud-Speaker Casing, of which the following is a specification, reference being had to the accompanying drawing, forming part thereof.

The accompanying drawing is a perspective view of the loud speaker casing.

I claim:

The ornamental design for a loud speaker casing substantially as shown.

In testimony whereof I have signed the foregoing specification.

CLAIR L. FARRAND.
